UNITED STATES PATENT OFFICE.

RICHARD HENRY TATLOW, JR., OF DENVER, COLORADO.

MATCH-SAFE.

1,139,919.

Specification of Letters Patent.

Patented May 18, 1915.

Application filed April 22, 1914. Serial No. 833,582.

To all whom it may concern:

Be it known that I, RICHARD HENRY TATLOW, Jr., a citizen of the United States, residing at Denver, in the county of Denver and State of Colorado, have invented certain new and useful Improvements in Match-Safes, of which the following is a specification.

My invention relates to improvements in match safes and more particularly to safes of the type shown and described in United States Letters Patent granted to me October 15, 1912, No. 1,041,370, wherein provision is made for receiving a full box of unused matches and for the disposition of the burnt or used matches. In my aforesaid patent no provision was made for the ready removal of one or more used matches so that it was necessary for a person at work around a gas-range to use a fresh match each time a burner was lighted.

The object of my present invention is to construct a suitable receptacle for the depositing of the burnt or used matches and from which one or more of the same may conveniently be removed and, upon igniting the match from a lighted burner, use the flame thereof to light additional burners on a gas-stove. By thus utilizing the burnt or used matches after one burner of a gas-stove has been lighted great economy of matches is possible.

Another object of my improvement is to construct a match safe so that the fresh or unused matches may be conveniently removed and which owing to its novel construction will always disclose to the observer the quantity of fresh matches stored therein.

Still another object is to construct a receptacle of this character that is economical to manufacture, having a minimum of parts to get out of order, and which is compact in its arrangement of parts.

The above and other objects I accomplish by the means and in the manner hereinafter fully explained and as more particularly pointed out in the claims, reference being had to the accompanying drawings, forming a part of this specification, wherein similar reference characters identify corresponding parts in the various figures.

Figure 1 is a perspective view of my improved match safe or receptacle; Fig. 2 is a transverse horizontal section thereof taken on line 2—2 of Fig. 1; Fig. 3 is a transverse

vertical section thereof taken on line 3—3 of Fig. 1.

Referring to the drawings, 1 and 2 represent the front and rear walls respectively of my improved match safe which are provided at each end with parallel end-walls 3 that are arranged at substantially right angles to the plane of said front and rear walls. A suitable bottom 4 is provided that comprises a plate extending from end-wall to end-wall and from the rear-wall to the front-wall where it is upturned to form a shallow tray 5 extending across substantially the entire length of said receptacle.

The interior of the receptacle is preferably divided transversely into two vertical compartments by a vertically disposed wall or partition 6 that extends from the top to the bottom of the receptacle and has its lower edge portion provided with an extension 7 that projects beyond the vertical plane of the front wall 1 and inclines downwardly toward and merges into the outer edge of the tray 5, substantially as shown.

The lower portion of the front wall 1 is preferably cut away a short distance above the bottom of the receptacle to form the elongated opening through which access may be had to the interior and at a point substantially in the center of width of the left hand compartment the lower edge of the front wall is recessed as shown at 8. The central portion of the front wall in front of the right hand compartment is preferably provided with a relatively narrow elongated vertical slot 9 extending substantially from the top to the bottom thereof. Each of the end walls 3 is provided at its lower forward edge with an extension 3^a, that is substantially the same shape as the extension 7 of the partition so as to prevent the matches lying on the tray 5 falling off the ends thereof.

A top or cover 10 hinged along its rear edge to the upper edge of the rear wall closes the upper end of each compartment and the same is provided with a circular or other opening 11 above the left hand compartment. When in use a box of matches, from which the cover portion has been removed, is slid into the right hand compartment so that the open portion of said box will face the slot 9 in the front wall. The cut away lower edge of said front wall permits of the removal of the matches whenever desired.

and after said matches have been used they are dropped into the other compartment through the opening 11 in the cover. However, when it is desired to light another 5 burner on the gas-stove one of these burnt matches may easily be picked up off the tray 5 in front of the cut-away portion of the front wall, the extension 7 of the dividing wall or partition preventing the mixing of 10 the used and unused matches resting on the tray.

For the purpose of providing a suitable 15 striker for the unused matches, small strips of sand paper or other abrasive material α are secured to the front and side walls of the safe, and in order that the match safe may be 20 hung conveniently upon the wall, suitable openings γ are formed in the rear wall for the purpose of hooking the same over a nail or similar device.

Having thus described my invention what I claim as new and desire to secure by Letters Patent, is:—

1. A device of the kind specified comprising 25 a substantially rectangular receptacle divided transversely by a vertical partition into two compartments, the lower portions of the front walls of both of which are cut

away in substantially the same horizontal plane, a tray disposed across the entire width of said receptacle below the cutaway portions of said compartments, a cover for said receptacle provided with an opening above 30 one of said compartments, and the front wall of the opposite compartment provided with 35 means whereby the interior thereof is disclosed.

2. A match-safe comprising two compartments disposed side by side one of which is adapted to receive a box of matches, a cover 40 therefor provided with an opening above the compartment next the match-box compartment, both of said compartments having the lower portions of their front walls cut away in substantially the same horizontal plane, 45 and a laterally disposed tray common to both compartments extending across the entire width of said match-safe below the plane of the cutaway portions of the front walls thereof.

In testimony whereof I affix my signature in the presence of two witnesses:

RICHARD HENRY TATLOW, JR.
